UNITED STATES PATENT OFFICE.

HARRIE A. BALLARD, OF ASHLAND, MASSACHUSETTS, ASSIGNOR TO THE TURNER TANNING MACHINERY COMPANY, OF BOSTON, MASSACHUSETTS, A CORPORATION OF WEST VIRGINIA.

LEATHER-WORKING MACHINE.

SPECIFICATION forming part of Letters Patent No. 691,302, dated January 14, 1902.

Application filed September 16, 1901. Serial No. 75,552. (No model.)

To all whom it may concern:

Be it known that I, HARRIE A. BALLARD, of Ashland, in the county of Middlesex and State of Massachusetts, have invented certain new and useful Improvements in Leather-Working Machines, of which the following is a specification.

This invention has relation to machines for treating hides, skins, and leather, relating more particularly to that type of machines in which the hide or skin is folded about a flat support and is acted upon by a working surface or member consisting of a plurality of working edges arranged in a substantially flat plane, the support and the working surface being movable one with respect to the other. Heretofore in such machines the work-support had two operative faces against which the hide or skin was held, and it was moved between two oppositely-disposed working surfaces or members, so that the major portion of the skin or hide was engaged by them. That portion of the hide which passed over the end of the support, however, could not be reached by the working edges, and it was necessary to provide means for temporarily disengaging the working surfaces from the hide or skin and shifting the latter upon the support, so as to bring the untreated portion in position to be engaged by said working surfaces. This expedient for securing treatment of the entire surface of the hide or skin has not been productive of the best results, since the skin was thereby subjected to greater rubbing, scraping, or other treatment at one portion of its surface than at others, and consequently when it left the machine it was not uniformly finished, and, moreover, it necessitated the employment of automatic mechanism for separating the working surfaces from the hide or skin and temporarily rendering the machine inoperative.

The present invention has for its object the provision of a machine of the type referred to having means for effecting a uniform treatment of the skin or hide; and to this end the illustrated embodiment of the invention is shown as provided with a supplemental flexible working surface or member which is adapted to engage and treat that portion of

the hide or skin which lies around the end of the support without shifting it relatively to said support. The said supplemental working member consists of a plurality of flexibly-connected ribs or edges adapted to double about the end of the work-support and rub or scrape the desired portion of the hide or skin. The supports for the skins, of which there are preferably a plurality, are carried successively between the oppositely-disposed working surfaces or members by an endless carrier, and the supplemental working member is hung to intersect the path of the supports, so that as the end of each one of the latter emerges from the working surfaces or members it engages the said flexible member, which yields and permits the edges thereof to rub or scrape the skin or hide on the said end as the support moves along.

Referring to the drawings, which represent one embodiment of the invention, to which, however, it will be understood, I am not limited, Figure 1 represents a longitudinal section through the machine. Figs. 2, 3, and 4 represent the operation of the flexible supplemental working devices. Fig. 5 represents in face view a portion of the supplemental member and the adjacent devices.

The machine is provided with the usual frame, and so far as its general features are concerned it is quite similar to the one shown in the patents to William B. Turner, No. 584,123, dated June 8, 1897, and No. 615,656, dated December 6, 1898, to which reference may be had for a more detailed description of the mechanism herein briefly referred to.

The endless-chain carrier is indicated at 11, and it is mounted upon suitable sprocket-wheels 12 12 at the ends of the machine. The travel of the carrier is at an inclination, although it may be horizontal, if desired. The said carrier has operatively connected to it a series of flat tables or supports 13 in a manner substantially as shown in said Patent No. 615,656. 14 and 15 represent, more or less conventionally, oppositely-disposed working surfaces or members, each of which comprises a plurality of working ribs, edges, or other contrivances which are adapted to engage and rub or scrape a skin or hide. These members

are connected by equalizing devices, (not shown,) to which is attached the weighted arm 151, as in said Patent No. 615,656. The tables or supports are each provided with two flat faces with curved ends, and said tables are arranged to pass successively between the working surfaces or members, as shown in Fig. 1. Any suitable driving mechanism may be employed for actuating the carrier; but as said mechanism forms no independent part of this invention I have not seen fit to illustrate it. The working members are held yieldingly toward each other, whereby they separate slightly as the work-supports pass between them; but I have not illustrated the mechanism by which this is accomplished, as it is shown in the patents previously referred to.

16 16 represent yieldingly-mounted helically-bladed rolls placed in the path of movement of the support. These rolls operate to smooth out the wrinkles from the hide or skin or to otherwise treat it, as occasion may require, and they are located, respectively, in front of and in the rear of the working members 14 15. The said rolls likewise operate to hold the hide or skin upon the supports as the latter pass between them. They are driven by any suitable mechanism. (Not shown.)

As thus far described the machine possesses no features of my invention save as they are used in combination with the parts now to be described.

35 In operation the skin or hide is loosely folded over the support at the front end of the machine, so that it lies upon both faces thereof, with portions extending around the front end, as shown in Fig. 2. My present 40 invention is designed to provide means for treating the portions of the skin around the end of the support.

Stretched across the machine is a cross-bar 18, having arranged at regular intervals a series of pairs of lugs 19, and depending from said lugs is a series of chains. Each chain consists of a plurality of articulated links 20, formed in any desired way and each provided with a blade, rib, or edge 21. When the said 50 chains are hanging free from the cross-bar 18, the edges 39 lie in the same plane transverse of the path of movement of the supports and constituting a supplemental working surface or member which intersects the path of movement of the work-supports, so that when each support emerges from between the working surfaces 14 15 it engages said member, which yields and in so yielding causes the edges or ribs to successively engage and rub that portion of the hide or skin which is bent around the end of the work-support, as will be described more in detail. The ribs or edges of the chains are arranged so that they break joint. The effect of this is to prevent the 65 creasing of the hide or skin as it is engaged and treated by the supplemental member. Each pair of chains has the last two links

connected by a cross-bar 22, the remaining links being otherwise disconnected. There are sufficient chains in the series to effectively treat the largest hide or skin that may be conveniently placed upon the carrier, and they are long enough to subject the hide or skin at the end of the carrier to the same degree of scraping or rubbing that the portions of the hide on the flat surfaces of the support will receive from the members 14 15. Normally the chains hang perpendicularly and rest against the pressure mechanism. Any suitable pressure mechanism may be employed for holding the chains yieldingly when they are engaged by the support; but I shall describe one form which may be used. It consists of a roll 25, journaled upon a cross-bar 26, whose ends are secured in centrally-fulcrumed levers 27. The fulcrums 28 for the said levers may be attached to the frame of the machine or any suitable part thereof. The lower ends of the levers are connected by a cross-bar 29, on which is placed a weight 30. The weight causes the levers to assume the position shown in dotted lines in Fig. 4, so that the flexible member rests loosely against the roll 25. Hence when the front end of each support engages the flexible member the latter is held yieldingly, as shown in Fig. 2. During the first portion of the movement of each support as it emerges from between the working members it is caused to engage the flexible member near its fastened end, and as said support progresses farther it carries the flexible member with it, the free end of the latter being held frictionally by the pressure mechanism to cause said member to be doubled around the end of the support, as shown in said last-mentioned figure. As the flexible member is held on its fastened end the remainder of it is caused to be dragged around the end of the support, whereby the ribs or edges rub or scrape the hide or skin on the said end. When the free end of the flexible support rides over the roll 25, the said flexible member lies loosely upon the top of the support, as shown in Fig. 3. In order to prevent the roll 25 from engaging the skin on the under side of the table or support in such way as to scrape it, each of the tables is provided with a wedge or cam strip 31, which engages the roll and holds it in the position shown in Fig. 3, forcing it downward against the pressure of the weight 30. This cam or wedge projects beyond the rear end of the table, so as to hold the roll or pressure member in inoperative position long enough after the flexible member drops from the table in order to permit it to assume an operative position before the roll is released. The resistance of the flexible member is in a direction opposite to the path of movement of the carrier, so that the action of the edges or ribs of said member is in a direction directly opposite the path of movement of the carrier, so that the action of the ribs or edges of the flexible member is only on that portion of the

skin which is on the end of the support, said ribs or edges exerting but little pressure against the hide on or under the top faces of the support.

5 So far as I am aware I am the first to have provided a leather-treating machine of the type employing substantially flat supports about which a skin or hide may be doubled, with a flexible working member adapted to 10 engage and treat that portion of the skin or hide which is upon the end of the support without shifting said skin or hide, and I therefore in no wise limit myself to the particular form of working member which I have seen 15 fit to herein describe. Consequently the said machine may be changed or modified in many respects without departing from the spirit and scope of the present invention. Again, so far as I am aware I am the first to have provided 20 in combination with the flexible working member a pressure member or mechanism engaging the said member in order that the ribs or edges thereof may be caused to engage the skin or hide with the proper degree of pressure. The provision of the flexible 25 working member enables the successful treating of not only that portion of the hide which lies upon the end of the support, but by making it of the proper length the rubbing or scraping of the skin or the portion 30 specified can be carried on to the same extent throughout the whole area thereof, so that the skin is uniformly treated in this machine.

35 In explaining the construction and operation of the invention as embodied in a complete machine I have described features of which I am not the inventor, and therefore disclaim them, as follows: I do not claim 40 means, broadly, for treating the hide or skin upon the end of the support without shifting the skin, my invention consisting of a flexible member for accomplishing that purpose. I do not claim the combination of the stationary 45 members with the spirally-bladed rolls or the mechanism for driving said rolls.

Having thus explained the nature of the invention and described a way of constructing and using the same, although without attempting to set forth all of the forms in which it may be made or all of the modes of its use, I declare that what I claim is—

1. A machine of the character described, comprising a movable work-support and having two flat faces, whereby a skin or hide may be folded about the end of the support to lie against said flat faces, and means for uniformly treating the entire exposed area of said hide or skin, said means including members disposed in the path of the work-support to engage those portions of the hide or skin which are on said flat faces, and a supplemental member consisting of a series of ribs 55 flexibly connected together for engaging the doubled portions of said hide or skin which lie on the end of the support.

2. A machine of the character described,

comprising a work-support having approximately flat faces whereby a skin or hide may be doubled over the end thereof to lie against 70 said faces, working members for treating those portions of the hide or skin which lie against said faces, and a flexible member arranged to extend across the end of the work-support and having articulated ribs or edges 75 for treating that portion of the hide or skin which is on the curved end of the support.

3. A machine of the character described comprising a series of traveling flat work-supports, each adapted to have a skin or hide 80 stretched around its end, and a working member consisting of flexibly-connected ribs or edges disposed in the path of the work-supports adapted to successively engage and treat the skins on the ends of said supports. 85

4. A hide or skin treating machine having main working members, a supplemental working member provided with operative ribs or edges flexibly connected together, a flat work-support having an end over which the skin 90 may be folded, and means for effecting the engagement of the end of said work-support with the said supplemental member.

5. A hide or skin treating machine having a flexible working member consisting of a series of loosely-hung chains, with ribs or edges 95 projecting therefrom.

6. A hide or skin treating machine having main working members, a flexible working member with ribs or edges which break joint 100 with each other, a flat work-support having an end over which the skin may be folded, and means for effecting the engagement of the end of said work-support with the said supplemental member. 105

7. A machine of the character described comprising a traveling work-support, working members disposed to permit the passage of said support between them, and a yielding working member hung loosely across the path 110 of said work-support and adapted to yield to the action of said support whereby it is wiped around the end of said support.

8. A machine of the character described comprising a traveling work-support, working members disposed to permit the passage of said support between them, and a working member hung loosely across the path of said work-support and adapted to yield to the action of said support whereby it is dragged 115 around the end of said support said flexible member consisting of a series of chains having ribs or edges. 120

9. A machine of the character described comprising a traveling support, a flexible 125 working member hung loosely from a point above said support to project across the path thereof and having a free lower end, said member having parallel ribs or edges extending from side to side thereof. 130

10. A machine of the character described comprising a traveling support, a flexible working member hung loosely to intersect the path of movement of said support, whereby

said member is engaged by the end of said support and gradually raised until it slides along the upper face thereof, and finally drops off the rear end thereof.

5 11. A machine of the character specified comprising a support having flat faces and an end, whereby a skin or hide may be doubled around said end to lie against said faces, and a working member adapted to extend around 10 said end to engage and treat the skin thereon, and also to engage the skin on both faces of the said support, said support and said member being movable, one with respect to the other.

15 12. A machine of the character specified comprising a support having flat faces and an end, whereby a skin or hide may be doubled around said end to lie against said faces, and a working member adapted to extend around 20 said end to engage and treat the skin thereon, and also to engage the skin on both faces of said support, said member having operative edges or ribs arranged substantially longitudinally of said end of said support, and means 25 for moving said support and member, one relatively to the other in a path transverse to said ribs or edges.

13. A machine of the character specified comprising a support having flat faces and an 30 end, whereby a skin or hide may be doubled around said end to lie against said faces, and a member having a series of flexibly-connected parallel ribs or edges, said member being arranged and located with respect to said support 35 whereby when one is moved relatively to the other, the said ribs or edges will be engaged in succession by the end of the support.

14. A machine of the character specified, comprising a flexible working member, a pressure 40 member, and a flat work-support whose end is adapted to engage the said flexible working member.

15. A machine of the character specified comprising a work-support, a flexible working member, hanging loosely in the path of said support, and means for causing said flexible member to exert pressure against the end of the support.

16. A machine of the character specified 50 comprising a flat work-support about the end of which a skin or hide may be folded, a flexible working member, and means whereby said member is engaged with the hide or skin on the end of said support.

55 17. A machine of the character specified

comprising a work-support about the end of which a skin or hide may be folded, a flexible depending working member, adapted to be engaged by the end of said support, and means for engaging the loose end of said member, substantially as described. 60

18. A machine of the character specified, comprising a work-support, a flexible member depending in the path of the said work-support, and means located below the travel 65 or path of said support for pressing the loose end of said member against the work-support.

19. A machine of the character specified comprising a work-support, a flexible working member arranged to operate on the skin 70 on the end of the support, and a weighted pressure member for said flexible member.

20. A machine of the character described comprising a traveling work-support having flat faces and an end, a dependent flexible 75 member disposed in the path of said support for operating on that portion of the skin which lies on the end of the support, a pressure member for exerting pressure on the said flexible member, and means for holding said pressure 80 member in inoperative position to permit the resetting of said flexible member.

21. A machine of the character described comprising a traveling work-support, having flat faces and an end, a dependent flexible 85 member disposed in the path of said support for operating on that portion of the skin which lies on the end of the support, a pressure member located below the travel of said support and outside said flexible member, and means 90 on said support for moving said pressure member to inoperative position to permit the resetting of the flexible member.

22. A machine of the character described comprising a traveling work-support, having 95 flat faces and an end, a dependent flexible member disposed in the path of said support for operating on that portion of the skin which lies on the end of the support, a pressure member located below the travel of said support 100 and outside said flexible member, and a cam on said support for holding said pressure member in an inoperative position to permit the resetting of said flexible member.

In testimony whereof I have affixed my signature in presence of two witnesses.

HARRIE A. BALLARD.
